UNITED STATES PATENT OFFICE.

HENRY GANNEY, OF NEW YORK, N. Y.

ESCAPEMENT.

SPECIFICATION forming part of Letters Patent No. 635,729, dated October 24, 1899.

Application filed February 17, 1899. Serial No. 705,830. (No model.)

To all whom it may concern:

Be it known that I, HENRY GANNEY, a citizen of the United States, and a resident of New York city, in the county of New York and State of New York, have invented certain new and useful Improvements in Single-Beat Watches, of which the following is a specification.

My invention relates to improvements in the escapement mechanism of timepieces; and the object of my invention is to give to single-beat watches, like the chronometer and duplex, the certainty of action of double-beat watches, such as the lever and the horizontal, and at the same time to retain their superior time-keeping qualities. I attain this object in and by the mechanism illustrated here-with and particularly described hereinafter.

The essential feature of my invention is the employment of auxiliary impulse-teeth on an escape-wheel adapted to engage with a pallet when desired, but so arranged as to clear the same upon its return stroke or when it is not desired to so engage. By this arrangement a stronger impulse is obtained and the engagement is made at the right moment, as is also the disengagement, thereby saving the engaging friction common to the ordinary duplex.

I will now proceed to describe a mechanism embodying my invention and will then point out the novel features in the claims.

Figure 1 is an enlarged view in detail of an escape-wheel and pallet embodying my invention, the escape-wheel being shown in face elevation and the pallet in horizontal section. Fig. 2 illustrates a transverse section of the same; and Fig. 3 illustrates a slightly-modified form, but embodying the same invention. Figs. 4, 5, 6, and 7 are figures similar to Fig. 1, but showing the parts in different relative positions.

Similar reference characters designate corresponding parts in the several figures.

J designates an escape-wheel having a plurality of teeth L, of ordinary or well-known construction. In the escape-wheel here illustrated there are fifteen. There may of course be more or less, as may be desired. The escape-wheel is mounted upon a suitable axis, as is usual, and designed to be constantly impelled in one direction (that of the arrow in

Fig. 1) through a suitable train of gearing and a spring, all of which is old in the art and too well known to require detailed description herein, it forming no part of the present invention. The escape-wheel is further provided with fifteen supplemental teeth K, there being a corresponding tooth K for every tooth L. The function of these teeth will be more fully set forth hereinafter.

M designates a pallet mounted on a suitable axis and provided with a roller having a suitable notch therein, as is usual in the duplex, to engage with teeth L of the escape-wheel J. The pallet-axis has provided of course the usual or any desired form of balance-wheel and hair-spring, all in a manner and for a purpose well known. The teeth L of the wheel J tends to throw the pallet, with its balance-wheel, around in the direction of the arrow shown in connection therewith in Fig. 1 against the resistance of the hair-spring and the hair-spring is arranged to return the same. The pallet M is provided on its under side with a notch through which the teeth K are intended to pass at certain times.

The action of the escapement is as follows: Assuming the parts to be in the position shown in full lines in Fig. 1, a tooth of the escape-wheel will just have completed its full impulse on the pallet and the pallet (with its balance-wheel) will be revolving about its axis against the resistance of the hair-spring in the direction of the arrow. The escape-wheel will be held against further movement by the succeeding tooth L, which will bear against the roller. When the resistance of the hair-spring shall have accumulated sufficiently to overcome the momentum of the pallet and balance-wheel, the same will return in a direction opposite to that in which the arrow is pointing and the pallet will swing around, the recess q in the pallet M permitting the said pallet to clear the uprising tooth K in its passage. The teeth K may be called "impulse teeth." The notch in the roller also passes by the tooth L, the said tooth merely dropping slightly and being picked right up again as the said notch passes it while going in such direction. Fig. 4 shows one of the teeth L as about to engage the notch in the roller to drive the pallet, with its bal-

ance-wheel, &c., in the direction of the arrow in such figure. Figs. 5 and 6 show progressive movements in the same direction. Fig. 7 shows the escape-wheel stationary and the 5 pallet returning, the impulse-tooth being passed by the pallet by reason of the recess in the pallet. Upon the first return movement of the pallet the recess *q* will again pass the tooth *K*, the said tooth drawing out and 10 bearing against the front edge thereof, as shown in Fig. 5. The force of the hair-spring imparts such momentum to the balance-wheel and pallet that the same overthrows considerably, and the hair-spring then reacts and 15 forces the pallet back or in the direction of the arrow. The pallet then again passes the impulse-tooth by reason of the recess *q*. At about this time, however, the notch in the roller comes opposite one of the teeth *L*, which 20 tooth engages the said notch, and the escape-wheel being free to move forward does so and applies an initial impulse to the balance-wheel. The continued movement of the balance-wheel and pallet brings the parts to the 25 positions shown in dotted lines in Fig. 1, in which it will be seen that the tooth *L* has completed its action on the balance, the said tooth having cleared the notch in the roller. The impulse-tooth *K*, however, has just begun to 30 engage the front curved face of the pallet and will continue to drive the same until a full step of the step-by-step movement has been made by the escape-wheel and the parts are again in the position shown in full lines in Fig. 1. 35 The result of this will be a very full, clean, and sharp impulse given to the balance and given at the time it would do the most good.

It will be seen that the impulse-tooth does not engage the pallet until after it has passed 40 an imaginary line drawn through the axes of the balance and escape wheels. This obviates the engaging friction common to the ordinary duplex, in which the impulse-tooth engages by necessity with the pallet as great a distance 45 on one side of such a line as it remains in engagement on the other. Furthermore, this arrangement renders available the long curved face of the pallet, the curve of which may be so arranged as to diminish or increase 50 the force of the impulse, as may be desired.

A further incidental advantage in the manufacture of the escape-wheel is that the impulse-teeth, unlike the teeth of the ordinary duplex, are arranged in line with the other 55 teeth on said wheel, and hence can be cut together. I may vary the position of the impulse-teeth, however, from that shown in the drawings. I may, if I desire, place them at the extreme end, or I may place them at the 60 base of the other teeth. I have already constructed escapements in both manners and they have worked well. I have, however, in both cases retained the underlying principle

of the impulse-tooth and the pallet clearing themselves when not in coactive operation. 65

In Fig. 3 I have shown a slightly-modified form, in which the pallet is in the form of a pin which may be attached to an arm on the balance-axis or may be secured to the balance-wheel itself. In this case I widen the 70 impulse-tooth in order to get the required stroke and preferably cut away the outer face of the pin, as *N* in the drawings, on an arc described with the balance-axis in the center. This is designed to prevent a possible "set" 75 through a wedging action upon the return stroke of the balance.

What I claim is—

1. The combination in an escapement mechanism of an escape-wheel having a plurality 80 of teeth, a balance-roller having a notch with which the said teeth are adapted to engage, a plurality of auxiliary impulse-teeth, a pallet carried with the said roller and adapted to engage with the said auxiliary impulse-teeth, 85 said pallet being arranged with a clearance or recess between its outer extremity and its axis whereby it may pass clear of the impulse-teeth when returning or when not desired to engage therewith substantially as specified. 90

2. The combination in an escapement mechanism of an escape-wheel having a plurality of teeth, a balance-roller having a notch with which the said teeth are adapted to engage, a plurality of auxiliary impulse-teeth, a pallet 95 carried with the said roller and adapted to engage with the said auxiliary impulse-teeth, a recess or clearance arranged in said pallet whereby when said pallet and one of said impulse-teeth are on an imaginary line drawn through both the balance and escape wheel axes, the said pallet will pass the impulse-tooth without touching same substantially as specified. 100

3. The combination in an escapement mechanism of an escape-wheel having a plurality 105 of teeth, a balance-roller having a notch with which the said teeth are adapted to engage, a plurality of auxiliary impulse-teeth, a pallet carried with the said roller and adapted to engage with the said auxiliary impulse-teeth, 110 said pallet being arranged with a clearance or recess between its outer extremity and its axis whereby it may pass clear of the impulse-teeth when returning or when not desired to engage therewith, the outer extremity of said pallet being formed substantially on an arc of a circle described with the axis of the pallet as a center substantially as specified. 115

Signed at New York, in the county of New 120 York and State of New York, this 16th day February, A. D. 1899.

HENRY GANNEY.
